STRAND HANDLING DEVICE

Leo L. Weaver, Cranford, N. J., assignor to
 Western Electric Company, Incorporated, New
 York, N. Y., a corporation of New York

Application April 10, 1940, Serial No. 328,825

9 Claims. (Cl. 254—177)

This invention relates to a strand handling device, and more particularly to a device for threading a strand in a plurality of successive loops about two or more multi-grooved pulleys, 5 sheaves or the like.

In the arts which deal with the manufacture and use of a large variety of strands, threads, wires, cords, and the like, there are numerous occasions upon which a strand is passed in a 10 plurality of recurrent loops around two or more multi-grooved drums, sheaves, pulleys or the like. For example, in U. S. Patent 1,841,484, granted on January 19, 1932, to H. M. Larsen, there is shown a pair of multi-grooved sheaves over which 15 a strand being treated runs in a plurality of consecutive loops or passes. The process of "threading up" such an apparatus to commence operation initially or to recommence operation after an accidental breakage of the strand, has heretofore 20 been done usually by hand, a tedious and time-consuming procedure, often difficult because of cramped space within the apparatus and sometimes dangerous because of heated or electrically charged elements of the apparatus in close proximity to the path of the strand.

An object of the present invention is to provide a simple, effective and reliable device for threading a strand accurately and rapidly into the successive grooves of two or more multi-grooved 25 rotatable members such as sheaves, pulleys, drums or the like.

With the above and other objects in view, the invention may be embodied in a guide belt comprising a strand adapted to fit into the grooves of 30 the rotary member in question and having means to couple the two ends of the strand in side by side relation so that as the trailing end of the strand is about to leave any groove of a multi-grooved member, the leading end will enter the 35 next groove of the member.

Other objects and features of the invention will appear from the following detailed description of one embodiment thereof taken in connection with the accompanying drawing in which— 40 45

Fig. 1 is a diagrammatic view in side elevation of three multi-grooved sheaves over which a strand is to be threaded by means of a guide belt constructed in accordance with the invention and showing the belt in operating position on the sheaves;

Fig. 2 is a similar view thereof in front elevation; and

Fig. 3 is a fragmentary view showing the leading end of the belt entering a new groove.

For convenience let it be assumed that the upper sheave 10 is keyed or otherwise rigidly secured to its shaft 11, and that this shaft may be 5 driven from any suitable motor means (not shown). Further let the sheaves 12 and 14 be idler sheaves, freely rotatable either with or on their respective shafts 13 and 15. Each of the sheaves is provided, as shown, with a plurality 10 of circumferential grooves 16, 17 and 18 in the respective sheaves, in which a strand 19 is to be threaded in a series of recurrent loops over the two sheaves 10 and 14, to be tensioned by the sheave 12, which may be thought of as adjustable for this purpose toward and from the plane joining the axes of the shafts 11 and 15.

To effect this threading, the belt 20 is placed initially in the position shown in Fig. 2, but in the first grooves 161, 171 and 181 of the three 20 sheaves instead of in the third grooves as shown. The body of the belt generally is preferably a smooth surfaced strand of a cross-section adapted to fit closely into and of material adapted to cling frictionally in the grooves. Thus in the particular instance illustrated, the grooves are V-shaped and the cross-section of the belt is a corresponding rhombus. In other cases it might be square, circular, elliptical or of other form to correspond to grooves of other shapes. In the present 30 instance the belt may be thought of as of leather or rubber coated textile material or other suitable substance.

The two ends of the strand are not abutted and joined coaxially end to end as in ordinary belts. 35 Instead, they are overlapped a short distance and coupled together side by side to stand with their axes substantially parallel to each other and definitely spaced as far apart as the central planes of any two neighboring grooves 16, 17 or 18, it 40 being assumed that the spacings of these grooves are uniform and alike. As here shown, and best in Fig. 3, the leading end 21 and the trailing end 22 of the belt are spaced the required distance apart by a spacing member or block 23 interposed between them, and are rigidly held to the block and to each other by removable coupling bolts 24 passing through the belt ends and the block. Where the coupled and so endless belt 50 cannot be merely slipped into place over the ends of the sheaves to lie in the first grooves, the bolts 24 may be removed and the belt threaded into position and then coupled.

While in many instances it will be satisfactory 55

to have the body of the belt a single, entire and unbroken strand of inextensible material as described, it may be preferred in some cases to have the belt longitudinally elastically extensible.

- 5 In such a case the body of the belt may be a helix of spring wire or a suitably shaped strand of soft vulcanized rubber or otherwise made to be generally elastically extensible. Or the expedient adopted in the belt shown in the drawing 10 may be used. Here a short portion of the inextensible belt body is removed at any convenient point between its ends, and is replaced by a short length of suitable helical tension spring 25. If preferred, several such springs may be inserted 15 into the belt. It is then necessary that each such length of spring should be so coupled in place and so proportioned to the apparatus on which it is to be used that it will not be extended sufficiently, when approaching any sheave in operation, to throw the ends of the belt body which it joins sufficiently out of alignment to cause the belt to rotate.

The belt having been placed in the grooves 161, 171 and 181, the leading end of the strand 19 is 25 coupled to the trailing end 22 of the belt. This may be done directly, by any suitable means, or, as here shown, by means of a towing spring 26 attached at its forward end to the trailing belt end 22, and having the leading end of the strand 30 19 secured to its rear end, e. g. by a knot as indicated at 27.

The shaft 11 may then be set in motion to 35 drive the sheave 10 in the direction of the arrow of Fig. 1. The sheave 10 will then drive the belt 20 and thereby the sheaves 12 and 14. Fig. 2 shows the state of affairs as the belt is completing its second circuit of the sheaves from its initial position on them. The trailing end 22 of the belt is about to lay the leading end of the 40 strand 19 into the third one of the grooves 18 of the sheave 14, while the leading end of the belt is about to lead the belt into the fourth groove of the same sheave. Thus at each circuit of the belt around the sheaves, the belt 45 automatically steps along another groove on each sheave, drawing the strand 19 along behind it and laying the strand in the desired succession of loops or passes about the sheaves. As the belt comes away from the last groove of the last 50 sheave, the drive of the sheave 10 is stopped and the belt detached from the strand 19 and removed from the apparatus, leaving the strand completely threaded in place on the sheaves.

The embodiment herein disclosed is illustrative 55 and may be modified and departed from variously without departing from the spirit and scope of the invention as pointed out in and limited only by the appended claims.

What is claimed is:

60 1. A device for threading a strand in successive loops about a plurality of multi-grooved rotatable members, the said device comprising a flexible elongated member to extend around the plurality of rotatable members and having its ends overlapped and secured in side by side relation.

65 2. A device for threading a strand in successive loops about a plurality of multi-grooved rotatable members, the said device comprising a flexible elongated member to extend around the plurality of rotatable members, and means to secure the ends of the flexible member together in overlapping side by side relation.

70 3. A device for threading a strand in suc-

sive loops about a plurality of multi-grooved rotatable members, the said device comprising a flexible elongated member to extend around the plurality of rotatable members and having its ends overlapped and secured in side by side relation, in combination with means to attach the leading end of the said strand to the trailing end of the flexible member.

4. A device for threading a strand in successive loops about a plurality of multi-grooved rotatable members, the said device comprising a flexible elongated member to extend around the plurality of rotatable members, and means to secure the ends of the flexible member together in overlapping side by side relation, in combination with means to attach the leading end of the said strand to the trailing end of the flexible member.

5. A device for threading a strand in successive loops about a plurality of multi-grooved rotatable members, the said device comprising a flexible longitudinally elastic elongated member to extend around the plurality of rotatable members and having its ends overlapped and secured in side by side relation, in combination with longitudinally elastic means to attach the leading end of the said strand to the trailing end of the flexible member.

6. A device for threading a strand in successive loops about a plurality of multi-grooved rotatable members, the said device comprising a flexible longitudinally elastic elongated member to extend around the plurality of rotatable members, and means to secure the ends of the flexible member together in overlapping side by side relation, in combination with longitudinally elastic means to attach the leading end of the said strand to the trailing end of the flexible member.

7. A device for threading a strand in successive loops about a plurality of multi-grooved rotatable members, the said device comprising a flexible belt to extend around the plurality of rotatable members and consisting of a single flexible elongated member shaped in cross-section to fit the grooves of the members, and means to secure the ends of the flexible member together in overlapping side by side relation.

8. A device for threading a strand in successive loops about a plurality of multi-grooved rotatable members, the said device comprising a flexible belt to extend around the plurality of rotatable members and consisting of a single flexible elongated member shaped in cross-section to fit the grooves of the members, and means to secure the ends of the flexible member together in overlapping side by side relation, in combination with means to attach the leading end of the said strand to the trailing end of the flexible member.

9. A device for threading a strand in successive loops about a plurality of multi-grooved rotatable members, the said device comprising a flexible longitudinally elastic belt to extend around the plurality of rotatable members and consisting of a single flexible elongated member shaped in cross-section to fit the grooves of the members, and means to secure the ends of the flexible member together in overlapping side by side relation, in combination with longitudinally elastic means to attach the leading end of the said strand to the trailing end of the flexible member.
